UNITED STATES PATENT OFFICE.

HENRY PENCE, JR., OF ELDORADO, OHIO.

FARM-TRACTOR.

993,194.

Specification of Letters Patent. Patented May 23, 1911.

Application filed April 23, 1910. Serial No. 557,202.

To all whom it may concern:

Be it known that I, HENRY PENCE, Jr., a citizen of the United States, residing at Eldorado, in the county of Preble and State of Ohio, have invented certain new and useful Improvements in Farm-Tractors, of which the following is a specification.

This invention relates to farm tractors and is designed to construct a machine of this nature which will be simple, durable, and inexpensive.

It also contemplates the construction of the steering mechanism which will impart a slight resiliency to the forward rollers, but which will also be firm and secure in its operation.

A further object of the present invention is to construct a device of this nature, the forward rollers of which will operate between two rows while the rear wheels will straddle the rows and will operate upon one-half of the next adjacent rows.

With the above and other objects in view, this invention consists in the construction, combination, and arrangement of parts as hereinafter more fully described, claimed, and illustrated in the accompanying drawings, wherein—

Figure 1 is a top plan view of a farm tractor of the class described, constructed in accordance with the present invention, parts thereof being broken away; Fig. 2 is a side elevation thereof; Fig. 3 is a front elevation of the forward roller; Fig. 4 is a side elevation of a steering wheel illustrating the connection thereof with the steering drum; Fig. 5 is a fragmentary view of the steering mechanism.

Reference being had more particularly to the drawings, 10 indicates the side bars of the frame-work, being off-set at their forward extremities 10'. A plurality of transverse braces 11 are provided between the side bars and providing means whereby the same are rigidly secured together. A vertical bearing 12 is interposed between the forward braces 11, in which is rotatably mounted the stub-shaft 13, the lower extremity of said stub shaft being provided with the ears 14. A U-shaped bar 15 is pivoted between the ears 14 and has journaled at its terminals the shaft 16 of the forward rollers 17, said rollers adapted to roll substantially the space between two rows of corn, and the like. An angle flange 18 is secured to the outer end of said roller and

provides facilities retaining the tractor in an approximately straight line.

A semi-circular angle bar 19 is secured at its terminals to the U-shaped bar 15 and extends rearwardly to the off-set portion of the side bars 10. This angle bar operates between the brackets 26 and on the grooved pulley 27, rotatably mounted between the brackets 26, the groove in the pulley 27 being angular conforms with the angle of the angle bar. Superposed above the pulley 27 is a pulley 28 rotatably mounted between the brackets 26 and adapted to conform with the angle of said angle bar, thus clamping 70 between said pulleys the semi-circular angle bar 19. This angle-bar is also provided at its forward extremity with the vertical ears 20 in which are rotatably mounted the bolts 21.

A drum 23 is mounted between the brackets 24 of the side bars about which is wound a flexible member 25, said flexible member being secured to the rear terminals of the bolts, and centrally to the drum 23. 80 It will thus be seen that upon rotating the drum the forward rollers may be turned in the direction desired. In order to provide a means whereby the drum may be rotated a worm gear 22 is carried at one terminal 85 of the drum and cooperates with a worm 28 carried at the lower end of the shaft 29 journaled in the bearings 30, said shaft having at its upper extremity a wheel 31. This construction permits the drum to be 90 rotated in any direction desired by turning the wheel 31.

A driving shaft 31 is mounted on the frame adjacent and parallel to the axle 32, and is operated by the engine or motor indicated as A. At the extremity of the shaft 31 is rigidly carried the spur gear 33, said spur gear meshing with an annular gear 34, mounted in the wheel 35. The annular gear 34 is provided at spaced intervals with the 100 lugs or ears 36, which are centrally secured in the channel bar 37, each of said ears cooperating with one channel bar. Thus it will be seen that upon the rotation of the shaft 31, the gears 33 will be likewise rotated 105 thereby driving the wheels 35. In order that the width of the wheels 35 will be increased, an extension plate 38 is secured to the outer edge of each wheel by detachable plates 39, thus doubling or otherwise widening the 110 wheel.

The wheels 35 carried at the terminals of

the rear axle 32 are provided with the hub 40 from which extend the crossed spokes 41 of the tread 35 of the wheel, thus supplying a certain rigidity and strength to the wheel.

5 Having thus fully described my invention what I claim as new is:

1. In a traction engine, the combination with a frame, a rear axle carried by said frame, wheels carried by said rear axle, 10 means whereby said axle may be rotated, a U-shaped bar pivotally mounted on the forward extremity of said frame, an axle carried by the lower terminals of said U-shaped bar, wheels carried by said axle, a semicircular, horizontal, rearwardly extending angle bar carried by the downwardly extending portions of said U-shaped bar, parallel brackets on the under side of said frame, rollers carried by said brackets adapted to 15 conform with the shape of said angle bar, and means whereby said angle bar may be swung to swing said U-shaped bar about its pivotal point.

2. In a traction engine, the combination with a frame, a rear axle carried by said frame, wheels carried by said rear axle, 20 means whereby said axle may be rotated, a U-shaped bar pivotally mounted on the forward extremity of said frame, an axle carried by the lower terminals of said U-shaped bar, wheels carried by said axle, a semicircular, horizontal, rearwardly extending angle bar carried by the downwardly extending portions of said U-shaped bar, parallel 25 brackets on the under side of said frame, an angular curved roller carried by said brackets adapted to form a bearing for the outer side of said semicircular angle bar, a beveled roller superposed above said curved roller adapted to bear against the inner surface of said angle bar, a shaft rotatably mounted on said frame having an annular gear at one terminal thereof, a rotatably mounted steering-rod having a worm at its 30 lower terminals adapted to coöperate with said gear, and a flexible member wound about said shaft and secured to the terminals of said angle bar.

eled roller superposed above said curved roller adapted to bear against the inner surface of said angle bar, and means whereby said angle bar may be swung thereby swing- 40 ing said U-shaped bar about its pivotal point.

3. In a traction engine, the combination with a frame, a rear axle carried by said frame, wheels carried by said rear axle, 45 means whereby said axle may be rotated, a U-shaped bar pivotally mounted on the forward extremity of said frame, an axle carried by the lower terminals of said U-shaped bar, wheels carried by said axle, a semicircular, horizontal, rearwardly extending angle bar carried by the downwardly extending portions of said U-shaped bar, parallel 50 brackets on the under side of said frame, an angular curved roller carried by said brackets adapted to form a bearing for the outer side of said semicircular angle bar, a beveled roller superposed above said curved 55 roller adapted to bear against the inner surface of said angle bar, a shaft rotatably mounted on said frame having an annular gear at one terminal thereof, a rotatably mounted steering-rod having a worm at its 60 lower terminals adapted to coöperate with said gear, and a flexible member wound about said shaft and secured to the terminals of said angle bar.

In testimony whereof I affix my signature 70 in presence of two witnesses.

HENRY PENCE, JR.
